Primary Examiner—Doris V. Coles

[57] CLAIM

The ornamental design for a golf shoe spike protector, as shown and described.

DESCRIPTION

FIG. 1 is a perspective view of my new design, with a right golf shoe shown in phantom line;

FIG. 2 is a left side elevational view thereof, with the right side elevational view being a mirror image thereof;

FIG. 3 is a top plan view thereof;

FIG. 4 is a bottom plan view thereof;

FIG. 5 is a front elevational view thereof; and,

FIG. 6 is a rear elevational view thereof.

The broken line showing of part of a shoe in FIG. 1 is for illustrative purposes only and forms no part of the claimed design.
